UNITED STATES PATENT OFFICE.

JOSEPH E. TYNAN, OF PATERSON, NEW JERSEY.

SPINDLE-DRIVING DEVICE FOR SPINNING-MACHINES.

SPECIFICATION forming part of Letters Patent No. 415,827, dated November 26, 1889.

Application filed June 4, 1888. Serial No. 275,930. (No model.)

To all whom it may concern:

Be it known that I, JOSEPH E. TYNAN, of Paterson, in the county of Passaic and State of New Jersey, have invented an Improvement in Spindle-Driving Devices for Spinning-Machines, of which the following is a specification.

My invention is especially designed for use in that class of machinery in which either a single thread is twisted and wound or two threads are twisted, doubled, and re-twisted and wound; but my said invention may be used in other kinds of silk-twisting machinery and also in machinery for twisting 15 cotton or other thread.

Where the spindles of a spinning-machine are each driven by a separate belt, as is generally the case, said spindles are not always all driven at the same rate of speed; hence 20 there is inequality in the twist given to the threads. This irregularity of speed of the spindles is caused by the slip of the belts upon the spindles and driving-drum and by the varying tension of the belts.

25 An endless belt has passed along between two rows of pulleys to drive them simultaneously, as in English Patent No. 1,938 (old law) and United States Patent No. 4,215 to W. Baxter, and spindles for spinning have 30 been driven by such pulleys, and in some instances several spindles or groups of spindles with pulleys have been driven by one endless belt; but in case of one thread breaking it either had to be joined while running or else 35 all the spindles had to be stopped, and where stop mechanisms have been provided for each group of spindles they have either had separate belts or else were driven by friction-wheels that in practice are found to be more 40 irregular than belts.

In my improvements I employ one endless belt to drive numerous groups of supply and lay-up spindles, the belt passing between the pulleys of each group, so as to drive the lay-up spindles in the reverse direction to the supply-spindles, and I combine with this a drop-bar-stop mechanism to each group, so as to stop one group of spindles if a thread break without interfering with the action of 45 the belt on the other groups of spindles; and I further combine with the devices before named a brake mechanism to hold the pulleys

from being moved by the contact therewith of the traveling belt, and in carrying out this invention I cause the pulleys to press against 55 the belt by the force of springs and swing them away by a positive action.

In the drawings, Figure 1 is a plan view showing my improvement applied to a silk doubling and twisting machine, only a portion of the machine being shown and the spindles being represented without their spools or bobbins. Fig. 2 is an elevation of the parts shown in Fig. 1, with the spools or bobbins upon the spindle. Fig. 3 is a sectional 65 elevation at the line *x-x* of Fig. 2, the parts being shown in larger size. Fig. 4 is a sectional plan at the line *y-y* of Fig. 3. Fig. 5 is a rear view of the lower end of the drop-bar, showing also the ends of the spindle-carriers operated by said drop-bar.

A A are the frames of the machine, and B the spindle-rail supported by said frames A A.

In Figs. 1, 2, 3, and 4 the spindles are shown as arranged in groups of three, as in Letters 75 Patent No. 364,783, granted to me June 14, 1887. The spindles 3 3 carry the spools 6 6, that supply the single thread, and these threads, after being twisted, are laid together and wound upon the spool 8 of the spindle 5. 80

9 is the ring-rail carrying the ring-travelers, and this rail may be actuated in any manner for laying up the threads upon the spools 8.

The spindles 5 are supported and revolve in bolsters *a*, secured to the rail B, (see Fig. 85 3,) and said bolsters are ranged in a straight line lengthwise of the machine. The spindles 3 3 are in a line parallel with the spindles 5; but their bolsters or bearings *f* are mounted upon supports or carriers *c c*, pivoted at *e* to 90 projecting portions of the rail B.

E is the endless belt for giving motion to the two rows of spindles. This belt is carried by the drums F G upon shafts 13 14, respectively supported in bearings H H upon 95 the frame A, and motion is given to the belt by a belt from the driving-shaft of the machine passing around a pulley 16 upon the shaft 14. The endless belt in its travel passes between the two rows of spindles 3 3 and 5, 100 and said spindles are rotated by the contact of the edges of the belt with the pulleys *a' a'* and *i i* upon the spindles. The arrows upon Fig. 1 indicate the direction of travel of the

belt E and the direction of rotation of the spindles 3 3 and 5, the spindles 3 3 rotating in the opposite direction to that of the spindles 5, so as to give the proper twist to the 5 single and doubled threads.

In order to keep the endless belt in contact with all the spindles of the two rows, I mount the spindles 3 3 upon pivoted carriers c c, as aforesaid, and I provide a helical spring h for 10 each pair of spindle-carriers, as shown in Fig. 4, which springs draw the longer arms of said carriers toward each other and bring the pulleys a' a' of said spindles 3 3 against one edge of the endless belt, thereby forcing the opposite edge of the belt against the pulleys i i of the spindles 5 and insuring uniformity of contact of the belt with all the pulleys of the two rows of spindles. The longer arms of the spindle-carriers c c extend beyond the rear of the 15 rail B and receive between them the double inclined end of the link or drop-bar D, which drop-bar D is to be connected at its upper end to the lever of a stop-motion device, preferably such as that shown in my application for patent, Serial No. 256,728, filed December 2, 1887, it being understood that there is a drop-bar for each group of spindles 3 3 and 5. When 20 a drop-bar of any group of spindles falls from a thread breaking or otherwise, the inclined end of said drop-bar acts upon the longer arms of said spindle-carriers c c and causes said carriers to swing upon their pivots e, and the pulleys a' a' of that group of spindles are moved away from the belt and brought into 25 contact with the spring-brakes l l, which arrest their rotation. At the same time the spindle 5 is stopped by the arms m of the drop-bar coming into contact with the top surface of the pulley i of said spindle 5. When the 30 drop-bar is raised by the attendant after the broken thread has been joined, the pulley i of the spindle 5 is released and the spring h swings the spindle-carriers so as to move the pulleys a' a' away from the brakes l l and into 35 contact with the edge of the belt E, and the group of spindles is again put into motion by said belt. By this improvement all the spindles of each row will be driven at the same rate of speed, as there is a constant and uniform 40 pressure of the pulleys against the belt. The drop-bar D is guided in its movement by the pin d⁴, projecting from the end of the oil-tube d⁵ and passing into a slot in said drop-bar.

It is necessary that the endless belt should 55 travel in a straight line, or nearly so. If the endless belt is not sufficiently stiff, the pressure of the pulleys a' a' against said belt at places where there are no idler-pulleys opposite said pulleys a' a' might bend said belt and cause its edges to travel in undulatory lines, and the spindles 3 3 would be moving out of line of each other, which would interfere with the spinning operation. To prevent this I stiffen the endless belt by a band 60 t of sheet metal secured to the belts by rivets.

This metal band may be between the two thicknesses of leather of the belt, if the belt is of two thicknesses; or it may be applied to the outer surface of the belt, as shown. In either 70 case it prevents the belt stretching and stiffens it so that the belt will travel in a straight line and thereby keep all the spindles of the single row in line with each other.

I claim as my invention—

1. The combination, in a spinning-machine, with the spindles 3 for the spools that supply the thread, and the spindle 5 for the spool on which the twisted threads are laid, of the horizontal belt E, running between the pulleys of 80 the respective spindles, a yielding pressing device for applying pressure of the pulleys against the edges of the belt, pivoted carriers for the sockets of the spindles, and a bar acting upon the pivoted carriers to move the 85 pulleys out of contact with the edge of said belt, substantially as specified.

2. The combination, with the endless belt and the drums for carrying the same, of the spindle-rail, the spindle 5 and its pulley at 90 one side of the endless belt, the spindles 3 3 and their pulleys a' a' at the opposite side of said belt, pivoted carriers c c, upon which the spindles 3 3 are mounted, and a bar to act upon said pivoted carriers and move the pulleys a' a' away from the belt, and means for pressing the pulleys toward the belt, substantially as and for the purposes specified.

3. The combination, with the endless belt and drums for carrying the same, of the spindle-rail, the spindle 5 and its pulley at one side of the endless belt, the spindles 3 3 and their pulleys a' a' at the opposite side of said belt, the pivoted carriers c c, upon which said spindles 3 3 are mounted, the spring h, the 100 brakes l l, and the drop-bar D and arm m, substantially as and for the purposes specified.

4. The combination, with groups of spindles, each group having two supply-spindles 110 and one laying-up spindle, of an endless belt traveling longitudinally between the pulleys of each group and rotating the supply-spindles in one direction and the lay-up spindles in the other direction, and a stop mechanism 115 acted upon by the threads to each group of spindles, and moving supports for the spindle-sockets moved by the stop mechanism for relieving the pressure of the pulleys on the belt and stopping the said group if a thread 120 breaks without interfering with the rotation of the spindles in the other groups, substantially as specified.

5. The combination, with the groups of spindles and pulleys and the endless belt for 125 driving the same, of pivoted carriers for the spindle-sockets, stop mechanism for moving the pivoted carriers and relieving the pressure of the pulleys on the belt, and standing friction-brakes with which the pulleys come in 130 contact as they are swung from the belt, substantially as specified.

6. The combination, with the groups of spindles and pulleys and the endless belt for driving the same, of pivoted carriers for the spindle-sockets, a drop-bar for moving the
5 pivoted carriers and relieving the pressure of the pulleys on the belt, and standing friction-brakes with which the pulleys come in contact as they are swung from the belt, and a

brake on the drop-bar to come in contact with the pulley of the lay-up spindle, substantially to as specified.

Signed by me this 28th day of May, 1888.
JOSEPH E. TYNAN.
